UNITED STATES PATENT OFFICE.

SAUL SLOAN, OF HAMTRAMCK, MICHIGAN.

FENDER.

1,324,936.

Specification of Letters Patent.

Patented Dec. 16, 1919.

Application filed May 21, 1919. Serial No. 298,622.

To all whom it may concern:

Be it known that I, SAUL SLOAN, a citizen of Russia, residing at Hamtramck, in the county of Wayne and State of Michigan, 5 have invented certain new and useful Improvements in Fenders, of which the following is a specification, reference being had to the accompanying drawings.

This invention relates to certain improvements in fenders and has relation more particularly to a device of this general character especially designed and adapted for use in connection with automobiles, and it is an object of the invention to provide a device 15 of this general character which includes a foldable basket normally inoperative but which drops or opens into a working position upon engagement of the fender with a pedestrian or other obstruction.

20 It is also an object of the invention to provide a novel and improved fender of this character including a normally folded basket held in folded condition through the instrumentality of one or more latches and 25 wherein said latch or latches are released through the medium of a striking member comprised in the fender.

The invention consists in the details of construction and in the combination and arrangement of the several parts of my improved fender whereby certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood, I will now proceed to 40 describe the same with reference to the accompanying drawings, wherein:

Figure 1 is a view in top plan illustrating a fender constructed in accordance with an embodiment of my invention and in applied 45 position, the basket being in open position, the operating circuit for the latches being diagrammatically indicated.

Fig. 2 is a transverse sectional view taken through my improved fender as illustrated 50 in Fig. 1, the adjacent portion of the automobile being fragmentarily illustrated in elevation.

Fig. 3 is a view similar to Fig. 2 with the basket in open or working position.

55 Fig. 4 is an enlarged fragmentary view,

partly in section and partly in elevation, illustrating in detail the striking member as herein embodied with parts concomitant thereto.

Fig. 5 is a fragmentary view, partly in 60 horizontal section and partly in plan, of the structure illustrated in Fig. 4, and

Fig. 6 is an enlarged fragmentary sectional view, partly in section and partly in elevation, illustrating one of the latches as 65 herein included in holding or locking position, the section being taken substantially on the line 6—6 of Fig. 1.

As disclosed in the accompanying drawings, A denotes the front end portion of an 70 automobile and which supports in advance thereof an elongated and transversely disposed bar 1 which extends entirely across the machine. The opposite end portions of the bar 1 are provided with the forwardly 75 directed arms 2 of desired length. The arms 2 are substantially in parallelism and perpendicularly related to the bar 1.

Connecting the outer end portions of the arms 2 and normally in parallelism are the 80 tubular members 3 and 4. The members 3 and 4 are yieldable and preferably formed of rubber, although other insulating material which can be employed with facility may be substituted therefor.

Extending through each of the members 3 and 4 is a coil spring 5 which operates to normally maintain said member in substantially a straight position yet permits flexure thereof in the event of an impact or other 90 force being imposed thereon. The outer member 3 constitutes a striking member and the flexibility of the members 3 and 4 serves to prevent undue injury, particularly when the member 3 comes into contact with a 95 pedestrian.

The opposed faces of the members 3 and 4 have disposed therealong the contact plates 6 and one of said plates 6 is in connection with a source of electrical energy E 100 through a conductor a. Interposed in the conductor a is a switch 7 for a purpose which is believed to be obvious.

Each end portion of the second plate 6 is in electrical connection with the source E 105 by a conductor b as is clearly illustrated in Fig. 1 and for a purpose to be hereinafter more particularly referred to.

The basket B of the fender comprises a bottom frame 8, preferably rectangular in 110

form. The frame 8 is of any desired width but of a length substantially equal to the space between the arms 2, so that the end members 8' of said frame 8 are in vertical alignment with the arms 2. Arranged within the frame 8 is a fabric 9.

The inner extremities of the end members 8' are pivotally engaged with the opposite end portions of the bar 1 and more particularly with the lugs or brackets 10 depending therefrom whereby the frame 8 of the basket is supported for swinging movement in a vertical path.

The ends of the basket B each comprises a toggle member T operatively connected with an arm 2 and the forward end portion of an end member 8' of the frame 8, so that when the frame 8 of the basket is raised, the end member will be folded accordingly and as is particularly illustrated in Fig. 6. It is also preferred that the forward extremities of the end members 8' be provided with the rollers 11 so that, when the basket B is open, the frame 8 may readily ride over the roadway or other surface.

Each of the end members 8' substantially midway its length is provided in its inner face with a recess 12 in which engages, when the basket B is folded, a latch 14. The latch 14 is supported by the inner face of the adjacent bar 1 for swinging movement toward or from the end member 8' and said latch 14 is also provided with an upstanding tail 15 operatively engaged, as at 16, with the core 17 of an electro-magnet M interposed in a conductor b.

Normally the basket B is folded or compacted and is maintained in such position by the latches 14. When the member 3 comes into contact with a pedestrian or other obstruction, the same will flex inwardly, resulting in the plates 6 carried by both of the members 3 and 4 contacting. This contact closes the circuits for the electro-magnets M through the conductors a and b, resulting in the cores 17 being drawn inwardly and the latches 14 released from the end members 8'. Upon the release of the latches 14, the basket B opens mainly by gravity, but in order to facilitate and expedite the opening of the basket B, I find it of advantage to suitably secure to the under face of each of the arms 2 a spring 18 which constantly exercises pressure on the adjacent end members 8' when the basket B is folded or compacted.

I also find it of advantage to interpose between the inner member 4 and the bar 1, at the central portions thereof, the tubular members 19, preferably of rubber, or other yieldable material, and housed within each of the members 19 is an expansible member 20, herein disclosed as a coil spring, and which spring has direct contact with the member 4 and with the bar 1. By this ar-

angement, the members 3 and 4 are further maintained in their normal or straight position.

In order to assure the members 3 and 4, or more particularly the plate 6, being normally separated, I interpose between the central portions of said members 3 and 4 and preferably in alignment with the members 19, the compressible blocks 21, preferably of rubber.

From the foregoing description, it is thought to be obvious that a fender constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I also do not wish to limit myself to the use of my improved fender in connection with automobiles, as the same may also be readily employed in connection with street cars or other vehicles traveling in streets and roads or which may be employed in factories and in connection with other industries.

I claim:

1. A fender comprising a supporting member including a bar provided with forwardly directed arms, a basket having a bottom member engaged with the bar for vertically swinging movement, and toggle members interposed between and connected to the end portions of the bottom member and the arms.

2. A fender comprising a supporting member including a bar provided with forwardly directed arms, a basket having a bottom member engaged with the bar for vertically swinging movement, toggle members interposed between and connected to the end portions of the bottom member and the arms, and releasable means for normally maintaining the bottom member elevated.

3. A fender comprising a supporting member including a bar provided with forwardly directed arms, a basket having a bottom member engaged with the bar for vertically swinging movement, toggle members interposed between and connected to the end portions of the bottom member and the arms, releasable means for normally maintaining the bottom member elevated, a striking member supported by the arms, and means under control of said striking member for disengaging the releasable means from the bottom member of the basket.

4. A fender comprising a supporting member including a bar provided with forwardly directed arms, a basket having a bottom member engaged with the bar for vertically swinging movement, toggle members interposed between and connected to the end portions of the bottom member and the arms, releasable means for normally maintaining the bottom member elevated, 5 and means for urging the bottom member of the basket downwardly when the releasable means is disengaged therefrom.
5. A fender comprising a supporting means including a bar having forwardly directed arms, a pair of yieldable members connecting the arms, opposed faces of the members being provided with contacts, a foldable basket engaged with the bar and arms of the supporting means, electrically 15 operated latches coacting with the basket for maintaining the same normally folded, and an electric circuit for operating the latches, the contacts carried by the yieldable members being interposed in said circuit 20 and normally separated.
6. A fender comprising a supporting means including a bar having forwardly directed arms, a pair of yieldable members connecting the arms, opposed faces of the members being provided with contacts, a foldable basket engaged with the bar and 25
- arms of the supporting means, electrically operated latches coacting with the basket for maintaining the same normally folded, an electric circuit for operating the latches, 35 the contacts carried by the yieldable members being interposed in said circuit and normally separated, and means for maintaining said yieldable members normally separated. 40
7. A fender comprising a supporting means including a bar having forwardly directed arms, a pair of yieldable members connecting the arms, opposed faces of the members being provided with contacts, a foldable basket engaged with the bar and arms of the supporting means, electrically 45 operated latches coacting with the basket for maintaining the same normally folded, an electric circuit for operating the latches, 50 the contacts carried by the yieldable members being interposed in said circuit and normally separated, and yieldable bracing means coacting with one of said yieldable members. 55

In testimony whereof I hereunto affix my signature in the presence of two witnesses.

SAUL SLOAN.
